A. Q. NASH.

GAS SAVING DEVICE FOR INTERNAL COMBUSTION ENGINES.

APPLICATION FILED AUG. 9, 1918.

1,320,407.

Patented Nov. 4, 1919.

UNITED STATES PATENT OFFICE.

ALEXANDER Q. NASH, OF ST. LOUIS, MISSOURI.

GAS-SAVING DEVICE FOR INTERNAL-COMBUSTION ENGINES.

1,320,407.

Specification of Letters Patent. Patented Nov. 4, 1919.

Application filed August 9, 1918. Serial No. 249,104.

To all whom it may concern.

Be it known that I, ALEXANDER Q. NASH, a citizen of the United States, residing at the city of St. Louis, State of Missouri, have 5 invented a certain new and useful Improvement in Gas-Saving Devices for Internal-Combustion Engines, of which the following is a specification, reference being had to the accompanying drawing, forming a part 10 thereof.

This invention relates to a certain new and useful improvement in gas-saving devices for internal combustion engines, the principal object of my present invention being to provide a compact, simple, and inexpensive device for conveniently adding to the gas-mixture supplied to the engine combustion-chambers moisture or vapor-laden, preferably superheated air in varying volume proportionate with the demands of the engine, thereby rendering more perfect the combustibility, and increasing the efficiency and obtainable mileage, of the supplied gas-mixture, obviating carbonization in the engine and its cylinders, and effecting a saving in the amount of gas furnished or supplied to the engine.

With the above and other objects in view, my present invention resides in certain novel features of form, construction, arrangement, and combination of parts, all as will herein-after be described and afterward pointed out in the claims.

In the accompanying drawing, 35 Figure 1 is a vertical sectional view of an internal combustion engine gas-saving device constructed in accordance with and embodying my invention in preferred form; Fig. 2 is a plan view of the same;

Fig. 3 is a detail sectional view of the manipulative air-inlet valve; and

Fig. 4 is a diagrammatic view of a combustion-engine equipped with or including a gas-saving device of my invention.

Referring more particularly to the said drawing, in which like reference characters refer to like parts throughout the several views, 1 indicates a water-reservoir preferably in the form of a cylindrical tank or shell permanently closed at its bottom and removably closed at its top by a cover comprising a flange-ring 2 and a cap-plate 3 detachably secured to the ring 2 by screws 4, a gasket 5 being interposed between ring 2 and plate 3 to prevent leakage.

The cover-plate 3 is provided with a pair of threaded openings, threaded into one of which is the upper end of an air-supply pipe or tube 6 located within the tank 1. Also threaded in said one opening, in communication with the pipe 6, is the discharge-end of a longitudinally bored valve-member or casing 7 having longitudinally within its length slots 8—8, which communicate with the atmosphere and with the bore of valve-member 7. The bore of valve-member 7 is reduced, as at 9, to provide a so-called seat-opening for a reduced portion 10 of a manipulative valve proper 11 lengthwise slideable in the bore of member 7, valve 11 being 70 formed at its inner end with a tapering portion 12 for regulating or controlling the flow or admission of air through the casing-slots 8 and opening 9 into the tube 6. The valve 11 carries a cross-pin or the like 13 75 arranged to ride in the slots 8 and which provides a point of connection with an operating or manipulating rod 14 extended through the dash or instrument-board and its free end made conveniently accessible to 80 the automobile-driver. By means of the operating rod or member 14, the valve proper 11 may be slidably actuated in the casing 7 to regulate or control the volume of air supplied through the tube 6 into the tank or 85 reservoir 1, as may be desired or required, the air-supply being completely shut off when the portion 10 of valve 11 is seated in the opening 9. Preferably, as shown, the valve-casing 7 is equipped with a stuffing- 90 box 15 to provide a lubricated support for the sliding valve proper 11 and also, through friction, to maintain the valve proper 11 in its various adjusted positions with relation to the air-inlet-opening 9.

Threaded in the other opening of cover-plate 3, is one end of a tubular connection 16 leading from the tank or reservoir 1 to the gas-intake or manifold A of the engine, and which connection 16 has within its 100 length a coil 17 encircling the exhaust-manifold B of the engine, whereby the moisture or vapor-laden air flowing through connection or pipe 16 from the tank 1 will be heated to a temperature approximating or 105 higher than that of the gas-mixture entering the manifold A from the carburetor C.

Disposed within the tank or reservoir 1, substantially throughout its length, as shown, is a tubular lining 18 of suitable 110

capillary material, and arranged within the tank 1 to hold the lining 18 from collapsing, is a wire-mesh cage or the like 19.

Fixed to the tank 1 at its lower end and 5 communicating with the interior thereof, is an elbow 20, whose outer open end is presented upwardly and into which is secured a filler-tube 21 provided at its upper end with a closure-cap 22. To provide for drain- 10 age of the tank 1, the elbow 20 is provided with a removable plug or the like 23, as shown, the tank 1 being adapted to provide a source of water or moisture supply independent of the usual water supply for the 15 engine.

The filler tube 21 is of suitable height relatively to the tank 1, and, as here shown, tube 21 is approximately half the length of tank 1, and disposed crosswise within the 20 tank and fixed to the cage 19 to lie in a plane slightly above the plane of the upper end of tube 21, is a perforated preferably sheet metal diaphragm 24 adapted to obviate splashing of the contained water into the 25 upper part of the tank.

The lower or discharge-end of air-supply pipe 6 is disposed at some distance above the diaphragm 24 and consequently above the level of the contained water, as illus- 30 trated in Fig. 1, and disposed crosswise within tank 1 and suspended by the tube 6 at its lower or discharge end, is an air-spreading baffle-plate 25 apertured to accommodate pipe or tube 6, but otherwise 35 imperforate, plate 25 being spaced at its periphery from the lining 18 and cage 19, as shown, to provide an air-outlet passage immediately next the lining 18 for the air entering the tank through the tube 6.

40 In practice, the tank or reservoir 1 is suitably positioned within the hood of the automobile, and to that end is preferably provided with securing-means in the form of a clamp or the like 26 arranged to be 45 conveniently bolted to the dash or instrument-board of the machine, one end of the pipe or connection 16 being fitted into a suitable opening tapped in the intake-manifold A between its division-point and the 50 carburetor C, as seen in Fig. 4.

In use or operation, the tank 1 is partially filled with water through the filler-tube 21, the water rising only to approximately the level of the upper end of the tube 21. The 55 lining 18, being partially immersed in the contained water, by capillarity carries the water above the diaphragm 24, where a large part of the area of the lining 18 is exposed to the open interior of the tank 1 60 and to the evaporating action of the incoming air. Valve 11 being actuated to permit air to flow into the tube 6, the running of the engine creates a suction which draws air through the valve-opening 9 and 65 downwardly through tube 6 into the tank

1, the entering air being then spread by the baffle-plate 25 to impinge against, and by evaporation taking moisture from, the lining or wick 18. The air laden with moisture or vapor then flows outwardly through the 70 pipe or connection 16 to the intake-manifold A, being superheated in its flow through the coil 17. On entering the manifold A, the moisture or vapor-laden and heated air commingles with the gas-mixture entering 75 from the carburetor C and flows therewith into the several combustion-chambers of the engine, the said moisture or vapor-laden, heated air serving to increase the combustibility of the gas-mixture, to obviate carbonization in the engine and its cylinders, and by augmenting the efficiency of the gas-mixture effecting a saving in the amount of 80 gas supplied to the engine.

I am aware that minor changes in the 85 form, construction, arrangement, and combination of the several parts of my new gas-saving device may be made and substituted for those herein shown and described without departing from the nature 90 and principle of my invention.

Having thus described my invention, what I claim and desire to secure by Letters Patent is:

1. A device of the type described comprising a tank adapted to be partially filled with water and having an air-inlet above the level of the contained water, in combination with a tubular lining possessing capillarity disposed within the tank and arranged for partial immersion in the contained water, and a baffle-plate disposed within the tank to spread the incoming air to impinge against the lining, the tank having an outlet arranged for connection with the gas-intake of the engine. 95

2. A device of the type described comprising a tank adapted to be partially filled with water and having a controllable air-inlet above the level of the contained water, in combination with a tubular lining possessing capillarity disposed within the tank and arranged for partial immersion in the contained water, and a baffle-plate disposed within the tank to spread the incoming air 100 to impinge against the lining, the baffle-plate being spaced at its periphery from the lining and the tank having an outlet above the plane of said inlet arranged for connection with the gas-intake of the engine. 110

3. A device of the type described comprising a tank adapted to be partially filled with water, in combination with an air-supply pipe located within the tank and having its discharge-end above the level of the contained water, means for controlling the admission of air into the tank through said pipe, a tubular lining possessing capillarity disposed within the tank and arranged for partial immersion 115

- in the contained water, and a baffle-plate suspended within the tank at the discharge-end of said pipe for spreading the incoming air to impinge against the lining, the baffle-plate being spaced at its periphery from the lining and the tank having an outlet above the plane of the discharge-end of said pipe arranged for connection with the gas-intake of the engine.
- 10 4. A device of the type described comprising a tank adapted to be partially filled with water and to provide a source of moisture-supply independent of the engine, in combination with an air-supply pipe located 15 within the tank and having its discharge-end above the level of the contained water, means for controlling the admission of air into the tank through said pipe, a tubular lining possessing capillarity disposed within the tank and arranged for partial immersion in the contained water, a baffle-plate suspended within the tank at the discharge-end of said pipe for spreading the incoming air to impinge against the lining, and a splash-preventing diaphragm disposed within the tank below the plane of the baffle-plate, the baffle-plate being spaced at its periphery from the lining and the tank having an outlet above the plane of the discharge-end of said pipe arranged for connection with the gas-intake of the engine.
- In testimony whereof, I have signed my name to this specification.

ALEXANDER Q. NASH.
